CLAIM

The ornamental design for a combination toilet cleaner and water conservation device, as shown and described.

DESCRIPTION

FIG. 1 is a front, top and side perspective view of the combination toilet cleaner and water conservation device embodying the design of the present invention;

FIG. 2 is a left side elevational view thereof, the side opposite being a mirror image of the side shown in FIG. 2;

FIG. 3 is a front elevational view thereof;

FIG. 4 is a rear elevational view thereof;

FIG. 5 is a top plan view thereof; and,

FIG. 6 is a bottom plan view thereof.
